UNITED STATES PATENT OFFICE.

NICHOLAS BECK, OF SEATTLE, WASHINGTON.

SKIRT AND WAIST HOLDER.

1,134,176.

Specification of Letters Patent.

Patented Apr. 6, 1915.

Application filed February 26, 1914. Serial No. 822,053.

To all whom it may concern:

Be it known that I, NICHOLAS BECK, a subject of the German Emperor, and resident of Seattle, King county, Washington, have invented certain new and useful Improvements in Skirt and Waist Holders, of which the following is a specification.

My invention relates to articles of personal wear and consists of a skirt and waist holder.

The object of my invention is to provide an effective, simple and cheap device for holding both skirts and waists, and one which will not be objectionable because of its bulk, and by the use of which the skirts and waists may be securely held in place.

In the accompanying drawings I have shown my invention in its preferred form of construction.

Figure 1 shows my invention as applied in use. Fig. 2 is an elevation of the inner side of the same.

My invention is composed of two parts, a plate, as 1, which is provided with garment-engaging means and a hook or suspension member secured to said plate.

The device is designed for being placed upon a belt by which it may be secured at the waist, but the waist band of a skirt may serve the same purpose.

The plate 1 has a tongue or tongues 2, preferably two in number, and integral therewith. In practice these would most readily be formed by stamping them out of the body of the plate, as has been shown in the drawings. The material should preferably be resilient enough to permit springing the tongues and the plate to permit insertion of fabrics, as the bottom of a waist, between them.

A hook 3, connected with the tongues 2, extends upward and has its uppermost end bent over to form the hook 33 which is adapted for hooking over a corset lace or for hooking engagement with another article of wearing apparel. This hook is hinged to the tongues 2, as is shown at 31, so that the plate may be placed in the most convenient position for insertion of the bottom of the waist.

The hook 33 is preferably rounded on its upper edge 34, or at the point of bend, to thereby prevent a sharp corner where it engages the corset lace. In case no rear laces are used on the corset a loop may be

secured at the proper place, and in case no corset is worn, the loop may be secured to any garment which is worn under the waist.

The spreading of the arms 30 of the hook member, will serve to pass and accommodate 60 a button on the waist, should such exist at this place, as is quite probable, as waists commonly button at the back.

In using this device the hook 33 is secured in place on a corset lace, or upon such other 65 support as may be used, and then the lower edge of the waist is inserted between the tongues 2 and the body of the plate 1. The order of doing these acts might, however, be reversed. The bottom edge of a 70 waist as it would be placed in the device is shown by the dotted line 7. The belt 5, if this is used, is then fastened about the waist. The pressure produced by this belt clamps the bottom of the waist between the tongues 75 and the body of the plate 1. This holds by clamping between smooth surfaces, so that there is no possibility of tearing the garment. The skirt is placed with its upper edge above the upper edge of the plate with 80 which it engages and is prevented from dropping. The upper edge of the plate 1, before tightening the belt, tends to stand out slightly. The belt or waist band of the skirt lies above this upper edge and, con- 85sequently, when drawn snug, draws the waist band over this edge, which thereby engages the skirt to support it. As the lower edge of the waist has been inserted between the body of the device and the tongues 2, 90 the upper edge of the body 1 will thereby be held sufficiently outward to securely engage and support the waistband of the skirt. If desired a strip of fabric may be secured to the inner side of the skirt waist, so that it 95 may be inserted between tongues 2 and the plate 1, to better insure holding the skirt in place.

To provide means for suspending other garments from the plate 1 I have shown it 100 as provided with holes 6 close to its lower edge into which hooks or pins may be inserted.

What I claim as my invention and desire to patent is:

1. A skirt and waist holder comprising a plate having a pair of vertically extending tongues cut therefrom, a suspension hook having branching arms pivotally secured by their ends to the upper free ends of said 110

tongues, the plate being provided with a belt receiving guide at each end, outwardly from the tongues.

2. A skirt and waist holder comprising a plate having vertically extending tongues cut therefrom, with their free ends upward, and a suspending hook pivoted to the upper ends of said tongues, the body of said plate being provided with means for holding a securing belt thereon.

3. A skirt and waist holder comprising a plate having vertically extending tongues

Copies of this patent may be obtained for five cents each, by addressing the "Commissioner of Patents, Washington, D. C."

cut therefrom with their free ends upward, and also having belt receiving slots in the body of the plate at its ends, and a suspending hook pivoted to the upper or free ends of the tongues.

In testimony whereof I have hereunto affixed my signature this 21st day of February, 1914.

NICHOLAS BECK.
